DRIVING MECHANISM FOR SLEEVE VALVES

George Stephen Kammer, Middleton, near
Ilkley, EnglandApplication July 17, 1941, Serial No. 402,887
In Great Britain July 16, 1940

7 Claims. (Cl. 123—81)

The invention relates to the driving of sleeve valves in internal combustion engines. It can be applied with particular advantage to two-stroke cycle engines and especially those having the scavenging arrangements disclosed in my co-pending patent application Serial Number 405,-096, filed August 1, 1941.

The main object of the invention is to provide a cyclic variation in the movement of the sleeve, with a prolonged dwell around the inner dead centre of the sleeve travel, that is to say when the sleeve is nearest to the cylinder head.

It is a further object of the invention to provide a cheap mechanism of this kind which will operate satisfactorily.

The applicant has already disclosed mechanisms for the purpose in view, but such mechanisms may sometimes be too bulky and heavy when applied to small engines. The present invention aims at providing a mechanism of light weight, small bulk and having few parts of such form as to require complicated jigs or expensive finishing operations. Thus the present driving mechanism is adapted for mass production.

A further object of the invention is to obtain an asynmetrical variation in the movement of the sleeve in regard to its inward and outward strokes. Such a variation could be obtained with the earlier mechanisms referred to but at the expense of some complication in construction. The mechanism according to the present invention is bound to produce a certain asymmetry in the motion, though such asymmetry may be made so small as to be practically negligible. The advantage of the asymmetry is that the sleeve can be made to move faster on its outward travel than on its inward travel. Consequently the engine can be timed for a more rapid exhaust port opening and have admission ports of larger area than previously. The open area of the admission port integrated with respect to time is then substantially increased over that of an engine with symmetrical sleeve motion.

According to the invention the sleeve valve of a two-stroke internal combustion engine is driven through a drag-link mechanism having unequal crank lengths.

A drag link mechanism is to be understood as meaning a driving mechanism which comprises two cranks with axes of rotation set on parallel but non-aligned shafts, and a link joining the pins of the two cranks, so that both cranks execute the same number of revolutions per minute,

but the instantaneous angular speeds of the cranks are different. If the driving crank is rotated at a uniform angular speed, the driven crank will rotate at a higher angular speed at one part of its travel and at a lower angular speed at another part. It is not considered necessary here to enter into a mathematical discussion of the mechanism, but it should be pointed out that with beyond certain limiting relative dimensions of crank, link and spacing of centres a mechanism can be obtained which will only oscillate the driven crank. Such a mechanism falls outside the scope of the above definition and accordingly outside the scope of the present invention.

In the preferred construction according to the invention the sum of the length of the drag link and the throw of the driven crank exceeds the sum of the separation of the shaft centres and the throw of the driving crank by an exceedingly small amount, which may be of the order of .001" or .025 mm., the driving crank then being the one with the larger throw.

The accompanying drawings serve to explain the principle of operation and show some embodiments of the invention, and therein—

Figure 1 is a line diagram drawn to certain relative dimensions.

Figure 2 is an end view of one form of driving mechanism having the same relative dimensions.

Figure 3 is an elevation partly in section corresponding to Figure 2.

Figure 4 is a diagram showing the resulting valve movement plotted against engine crank angle.

Figure 5 is a transverse section through a preferred embodiment of the invention.

Figure 6 is an axial section of the same, and

Figure 7 is a half end elevation of the same.

Referring first to Figure 1, the driving crank is centred at X and has a length in arbitrary units of 156. The driven crank is centered at O, the length OX being 72 and the crank length 84. The link length is 145, and it will be seen that the sum of driven crank and link is 229, while the sum of driving crank and centre distance is 228.

The pin of the driven crank 1 follows the smaller circle and that of the driving crank 2 the larger circle, and in this instance the two circles touch each other since $84 + 72 = 156$. The circle marked 2 is divided into equal arcs of $22\frac{1}{2}^\circ$, and for each point the drag-link 3 is drawn in to define the position of the pin of the crank 2 on the smaller circle. At the upper part of

the circle these points are closely spaced, indicating a pronounced dwell of the driven crank here, while at the lower part of the circle the points are more widely spaced. The right-hand side of the circle shows a wider spacing of the points than the left, or, in other words, the valve moves more rapidly on its outward travel than on its inward travel.

Referring now to Figures 2 and 3, a rotary member 1 is mounted on an axis O by means of roller bearings 4 in a housing 5 attached to the engine crank case. A rotary member 2 is mounted on an axis X by means of roller bearings 6 in a housing 7 also attached to the engine crank case. Crank pins 8 and 9 extend on opposite sides from the member 1 and in line with each other. The crank pin 9 is connected by a sliding ball and socket joint 10 to the sleeve 11.

The rotary member 2 is keyed to a driving shaft 12, which is positively driven from the engine crank shaft. A crank pin 13 on the member 2 is linked to the crank pin 8 on the member 1 by the drag-link 3 through roller bearings.

In Figure 4 the sleeve travel is plotted against the angular movement of the member 2 starting from the point marked I in Figure 1 as origin. The sleeve reaches its inner dead centre position at about 30° but is practically stationary from about 350° through 0° to 130°. It reaches its outer dead centre position at 235°. The piston dead centres are at 88½° and 268½°, the points being marked C and A respectively.

With a sleeve travel of 28 and piston stroke of 110 units, the sleeve edge movement, represented by the curve 14, first uncovers the exhaust at the point Z at 193½°. The piston travel is represented by the curve 15. The upper edge of the admission ports in the sleeve is represented by the curve 16. Curves 15 and 16 intersect at the point W at 226°, where the admission ports commence to open and to admit scavenging air.

The sleeve reaches its outer dead centre position at B at 235°, and the admission ports open rapidly, until at 270° they reach their maximum opening of 18 length units. At 295° the exhaust ports close, and from then until 320° the charge of fresh air enters, after which compression starts. The phase displacement between the piston and valve at the outer dead centre is 33½°.

To provide a different timing, which may be desirable in some cases, the dotted curve 17 might be used for the upper edge of the admission ports in the sleeve.

The timing may also be varied by altering the phase difference or by changing the length of travel of the sleeve.

The arrangement shown in Figures 2 and 3 is set out as an example of a constructional form of the invention and has been chosen on account of its simplicity for the purpose of explanation. Such an arrangement would, however, require considerable space in the axial direction of the shafts. The preferred arrangement is shown in Figures 5, 6 and 7 and is drawn to the same relative dimensions as Figures 2 and 3.

One difference is that the crank 9 is diametrically opposite to the crank 8. The bottom position of the crank 8 thus corresponds to the inner dead centre of the sleeve. Partly on account of this inversion the whole mechanism has been compressed in the axial direction. The housings 5 and 7 are combined into one member 18 having an aperture 19, through which a gear wheel (not shown) can mesh with teeth 20 cut on the

periphery of the member 2 between two roller races. The member 2 is recessed to accommodate the link 3 and the crank pin 8 of the member 1. Both crank pins 8 and 9 are hollowed for lightness as may be seen from an inspection of Figure 6, where the section is taken through the center lines of the crank pins.

With the arrangement now disclosed the overall dimensions of the driving gear can be made about 35% less than those of the driving gear according to my Patent No. 2,197,107, issued April 16, 1940, and the production costs can be reduced to one-sixth or one-seventh as compared with the earlier mechanism.

Various modifications may be made in the constructional forms actually shown and described without departing from the spirit and scope of the invention as defined in the appended claims.

What I claim is:

1. In an internal combustion engine with a sleeve valve having an oscillating and reciprocating motion, means to provide a cyclic variation in the movement of said sleeve valve comprising a rotary member driven on a fixed axis, a crank 25 on the rotary member, a second rotary member with its axis fixed and parallel to but displaced from that of the first rotary member, a crank on the second rotary member having a throw different from that of the crank on the first 30 rotary member, a link joining the two cranks, and a driving connection between the second rotary member and the sleeve valve.

2. In a two-stroke internal combustion engine with a sleeve valve having an oscillating and reciprocating motion, means to provide a cyclic variation 35 in the movement of said sleeve valve comprising a rotary member driven on a fixed axis at the same speed as the engine, a crank on the rotary member, a second rotary member with its axis fixed and parallel to but displaced from that of the first rotary member, a crank 40 on the second rotary member having a throw smaller than that of the crank on the first rotary member, a link joining the two cranks, and a driving connection between the second rotary member and the sleeve valve.

3. In an internal combustion engine with a sleeve valve having an oscillating and reciprocating motion, means to provide a cyclic variation 50 in the movement of said sleeve valve comprising a rotary member driven on a fixed axis, a crank on the rotary member, a second rotary member with its axis fixed and parallel to but different from that of the first rotary member, a crank 55 on the second rotary member having a throw smaller than that of the crank on the first rotary member, a link joining the two cranks, and a driving connection between the second rotary member and the sleeve valve, in which the 60 sum of the throw of the second crank and the length of the link only slightly exceeds the sum of the throw of the first crank and the distance between the axes of the rotary members.

4. In an internal combustion engine with a sleeve valve having an oscillating and reciprocating motion, means to provide a cyclic variation 65 in the movement of said sleeve valve comprising a rotary member driven on a fixed axis, a crank on the rotary member, a second rotary member with its axis fixed and parallel to but displaced from that of the first rotary member, a crank 70 on the second rotary member having a throw different from that of the crank on the first rotary member, a link joining the two cranks, another crank on the second rotary

member, and a universal and sliding joint connection between the last-named crank and the sleeve valve.

5. In an internal combustion engine with a sleeve valve having an oscillating and reciprocating motion, means to provide a cyclic variation in the movement of said sleeve valve comprising a rotary member of disc shape in a fixed housing, a crank pin on the rotary member, a second rotary member of disc shape smaller than the first rotary member and rotatable in the same housing on an axis spaced from but parallel to that of the first member, a crank pin on the second member projecting into a recess in the first member, a link within the recess joining the two crank pins, and a driving connection between the second rotary member and the sleeve valve. 15

second rotary member and the sleeve valve. 6. In a two-stroke internal combustion engine with a sleeve valve having an oscillating and reciprocating motion, means to provide a cyclic variation in the movement of said sleeve valve comprising a rotary member of disc shape driven at the same speed as the engine in a fixed housing, a crank pin on the rotary member, a second rotary member of disc shape smaller than the first rotary member and rotatable in the same

housing on an axis spaced from but parallel to that of the first member, a crank pin on the second member projecting into a recess in the first member, a link within the recess joining the two crank pins, a further crank on the side of the second rotary member away from the first rotary member, and a sliding and universal joint between the last-named crank and the sleeve valve.

10 7. In an internal combustion engine with a sleeve valve having an oscillating and reciprocating motion, means to provide a cyclic variation in the movement of the said sleeve valve comprising a fixed housing, a disc member rotatable
15 in the housing, roller bearings between the disc member and the housing, a crank pin projecting from the disc member, a second disc member rotatable in the housing on an axis parallel to but spaced from the axis of rotation of the first disc member, roller bearings between the second disc member and the housing, a crank pin projecting from the second disc member into a recess in the first, a link coupling the two crank pins, and roller bearings between each crank pin and the link.
